CARBURETING APPARATUS

Roy F. Ensign, San Marino, Calif., assignor to
 Ensign Carburetor Co., Ltd., Huntington Park,
 Calif., a corporation of California

Application September 26, 1936, Serial No. 102,718

7 Claims. (Cl. 48—180)

This invention pertains generally to fuel feeding and carbureting apparatus for internal combustion engines, and in one of its more specific major aspects deals with apparatus for supplying engines with gaseous fuel at substantially constant pressure and at variable rates in conformity with the requirements of the engine under different conditions of operation. The invention also contemplates the provision of a carbureting apparatus which may operate selectively on either gaseous or liquid fuel.

With particular reference to that aspect of the invention dealing with the supply of and carburetion with natural gas or other forms of gas for the operation of internal combustion engines, my objects, generally, are threefold: First, to regulate the pressure of the gas fed to the carburetor so as to maintain substantially constant pressure under all loads, preferably a pressure close to or slightly under atmospheric pressure; second, to produce the correct mixture of gas and air for the engine under all speed and load conditions; and third, to make it possible to obtain a perfect mixture during cranking of the engine and initial operation up to the point where normal operating conditions obtain. The latter object is particularly stressed because of the difficulties heretofore involved in starting. In order that a more comprehensive understanding of the difficulties which are overcome by the invention may be had at the outset, it may be well to refer briefly to the conditions giving rise to the problem and how, in general, the invention provides the solution.

In order to obtain the required volume of mixture to meet the power requirements with a gas carburetor the venturi must necessarily be relatively large and consequently the fuel metering depression therein at cranking or idling speeds is not sufficient to give a continuous proper proportioning of the fuel and air mixture. In accordance with the invention, I overcome this difficulty by providing means whereby during cranking or idling speeds, the engine may be supplied with the correct amount of gaseous fuel without having to depend on the normal Venturi depression at these speeds, thereby overcoming the above mentioned difficulties.

The present gas carbureting apparatus is generally similar to that described in a copending application, Ser. No. 26,768, filed June 15, 1935 by O. H. Ensign on Gas pressure regulator, now Patent No. 2,073,298, March 9, 1937, but differs essentially with reference to the means for obtaining proper fuel mixtures at starting and idling

speeds. The O. H. Ensign application embodies generally the combination of a differential gas pressure regulator and gas carburetor, and in that apparatus an amount of gas flow to the carburetor sufficient for starting purposes is produced by a manually operated priming device causing the pressure regulator to deliver gas independently of pressure conditions in the suction passage of the carburetor. While that type of priming device has proven satisfactory in many different types of installations, in others it has to some extent proved less efficient than the corresponding means embodied in the present invention, due to the fact that where the carburetor includes pipe connections to an air cleaner, these connections and the cleaner itself become filled with gas at starting, excluding the air and requiring considerable cranking to thin the fuel and air mixture being taken into the engine to the desired ratio at engine starting speed. Theoretically, of course, it would be possible to prime the regulator just sufficiently to deliver the correct amount of gas, but in practice such exactness of control is difficult, and usually the result is that, where the engine is cold, combustion occurs irregularly because the improperly proportioned fuel mixture does not have sufficient energy upon combustion to shear the oil films on the cylinder walls and to continue to operate the engine while it is still cold.

Viewed in one aspect, the invention may be regarded as providing for two stage carburetion to supply a combustible mixture of the proper proportions first at starting speeds, and then as the engine warms up, for normal operating speed. Briefly, the first stage carburetion is accomplished by providing within the suction passage of the carburetor a manually operated valve, independent of the throttle, which obstructs the suction passage and thereby creates a depression which causes the gas to flow from the regulator, such gas being delivered to the suction passage at the inlet side of the throttle through a severely restricted opening which is, in effect, imposed in the path of flow simultaneously with the operation of the valve. The second stage carburetion is effected by relieving the suction passage of the obstruction imposed by the said manually operated valve and by delivering to the suction passage a flow of gas under control of the throttle which is properly restricted for the normal operating requirements.

It is also an object of the invention to provide a carburetor capable of operating on either liquid or gaseous fuel. In accomplishing this object I

30

35

40

45

55

provide separate liquid and gas fuel nozzles discharging into the suction passage of the carbureter at the inlet side of the throttle, a suitable fuel feeding system for supplying liquid fuel from a constant level supply chamber to the liquid fuel nozzle, a pressure regulator for supplying gaseous fuel at substantially constant pressure to the gas fuel nozzle, and separate controls whereby the carbureter may operate selectively on liquid or gaseous fuel.

10 In this latter connection the invention contemplates as a further object, the provision of a float locking mechanism which will prevent wear in the parts when the carbureter is being operated on gas and the liquid supply unit is shut off.

15 Relative to the combination gas and liquid carbureter, my invention also contemplates gas feeding attachment which can readily be mounted on a standard liquid fuel carbureter to convert the same to a combination unit adapted for 20 operation with either liquid or gaseous fuel.

25 All the above mentioned features and objects of the invention, as well as further aspects and details thereof, will be best understood from the following description of certain typical and illustrative forms. For purposes of description reference is had to the accompanying drawings, in which:

30 Fig. 1 is a sectional view showing a typical form of gas fuel supply and carbureting apparatus embodying the invention, with the choke valve illustrated in an intermediate position;

35 Fig. 2 is a section looking upward on line 2—2 of Fig. 1, illustrating the carbureter valve mechanism and showing the shutter valve in normal operating position;

Fig. 3 is an end view of the air intake illustrating the choke valve construction contemplated by this invention;

40 Fig. 4 is a fragmentary section on line 4—4 of Fig. 1;

Fig. 5 is a view generally similar to Fig. 1, showing a combined gasoline and gas carbureter, the gas pressure regulator being shown in 45 elevation;

Fig. 6 is a sectional view showing a variational form of carbureter adapted to operate on either gasoline or gas;

Fig. 7 is a section on line 7—7 of Fig. 6; 50 Fig. 7a is a fragmentary section on the line 1a—1a of Fig. 6;

Figs. 8 and 9 are fragmentary sections on lines 8—8 and 9—9 of Fig. 6;

Fig. 10 is a fragmentary section on the line 55 10—10 of Fig. 9; and

Fig. 11 is a diagrammatic view illustrating means for simultaneously actuating the gas and liquid control valves in a combination unit so that the selective supply of gaseous and liquid 60 fuels is automatically controlled.

In Fig. 1 I show a gas fuel supply system comprising a pressure regulator, generally indicated at 10 for feeding gas at substantially constant, and preferably subatmospheric pressure, to the carbureter 11. It will be understood that in its broad aspects, the invention is not limited to the use of a pressure regulator or carbureter of any particular construction, or built according to the details shown in Fig. 1, but that any suitable regulator and carbureter combination, may be used so long as they contain parts in the operative relationships specified in the claims. The particular apparatus illustrated has however, been found especially suited to the purposes of the in-

vention, and hence may be regarded as representing a preferred construction.

I have illustrated a simple form of carbureter comprising a suction or fuel and air mixing passage composed of sections 12 and 13 connected together by screws 14, section 12 being attached to the engine manifold fuel and air intake 15. A venturi 16 is placed in the suction passage between the inlet 17 and outlet 18, a main fuel nozzle 19 discharging into the throat of the venturi under control of the usual throttle 20. Further details of the carbureter will be later described in connection with their operative relationships with the pressure regulator 10.

For a more complete discussion of the operation of pressure regulator 10, reference may be had to the patent of O. H. Ensign, referred to hereinabove, and a relatively brief description of the regulator details and operation will suffice for present purposes. The regulator body comprises three sections 21, 22 and 23 between which are clamped the main and pilot diaphragms 24 and 25. Pressure chambers 26 and 27 are provided below and above main diaphragm 24, the last mentioned chamber being defined by a transverse wall 28 within the intermediate body section 22. Chamber 29 above the pilot diaphragm 25, constitutes a reference pressure chamber whereby at all times a relatively constant pressure is applied to the upper surface of the diaphragm. The chamber 30, below the diaphragm, which is provided with a partition plate 31 held in place by an expansible lock ring 32, constitutes a variable pressure chamber.

High pressure gas supplied to the regulator from inlet 33 is deflected by a baffle 34 into chamber 26, from whence it passes under control of the main regulator valve 35 to the regulator outlet 36. The latter connects by way of pipe 37 with a fuel supply passage 38 formed within section 13 of the carbureter, the gas flowing from passage 38 under control of the mechanism, (to be described hereinafter) to nozzle 19 via passage 39. Main regulator valve 35 is attached to the main diaphragm 24 by lock ring 40 retaining the flanged head 41 of the valve stem 42 within a connecting member 43 fastened to the diaphragm. Upward movement of the diaphragm is resisted by springs 44 attached to the diaphragm and bearing against the body wall 28, the springs 50 acting to hold valve 35 in seated position when the pressures in the main diaphragm chambers 26 and 27 are balanced, or at such times as the pressure in pilot diaphragm chambers 29 and 30 is the same, for example when the regulator is 55 not in operation and atmospheric pressure is applied to both sides of the pilot diaphragm. By reason of the main valve, thus normally being held seated, the regulator when brought into operation, will deliver gas to outlet 36 at a sub-atmospheric pressure, and, by reason of the regulator being operated by suction communicated from the carbureter, will automatically shut off the gas supply to the carbureter as soon as such suction is discontinued when the engine stops.

A restricted flow of gas is permitted from the inlet 33 to chamber 27 above the main diaphragm by way of bushing 45 having a small calibrated orifice, and passage 46, these passages normally serving to balance the pressures applied to the opposite sides of the main diaphragm. In order to avoid or dampen out excessive vibrations of the main diaphragm with resultant irregularities in the movement of valve 35 and in the outlet 75

pressure, chamber 27 is placed in communication with a closed chamber 47 via orifice 48.

The operation of the main diaphragm 24 and the consequent actuation of the valve 35 was discussed in detail in connection with Fig. 4 of the copending O. H. Ensign patent hereinabove referred to. It suffices to say that when a positive suction is established in the fuel supply passage 38 that such suction is communicated through connections 37 and 36 and the passage indicated at 50—50' into the variable pressure chamber 30 below the pilot diaphragm 25 by way of a port 51. Port 51 is a restricted port and is located between the pilot diaphragm 25 and the plate 31. In addition to this port 51 the variable pressure chamber 30 is provided with a substantially unrestricted port indicated at 52, such port is located beneath the plate 31 and also communicates with the passage 50—50'.

The suction thus communicated to the variable pressure chamber 30 establishes a pressure differential between the two sides of the pilot diaphragm 25, such differential being effective to depress this diaphragm. When the pilot diaphragm 25 is thus depressed, it is effective to actuate the pilot valve mechanism generally indicated by reference numeral 53, structural details of which are also fully described in the copending O. H. Ensign patent hereinabove referred to. The minimum depression which will actuate the regulator to deliver gas therefrom is set by the size and compression valve of the spring 53' in the valve mechanism 53. The opening of the pilot valve 53 under the action of a depression in chamber 30 communicates the suction from the lower part of chamber 30 to chamber 27 at the upper side of the main diaphragm 24, causing such diaphragm to be elevated with the result that the main valve 35 is opened.

In order to accommodate for any pressure fluctuations at the air intake, which may occur due to the use of air cleaners or other devices, and to maintain a uniform pressure balance in the carbureting system at all times, it is preferable that the reference pressure chamber 29 above the pilot diaphragm 25 be connected to the air inlet passage 17 rather than being opened to the atmosphere. For the purpose of establishing this pressure communication, the section 23 above the pilot diaphragm is shown as being formed with a passage 55 which is connected through a fitting 56 and a tubing 57 with a pilot tube 58 which extends into the inlet end of the air passage.

For proper idling operation it is important that a positive suction be communicated to the variable pressure chamber 30 during such idling operations. This suction must be of sufficient magnitude to hold the main valve 35 open the required amount to supply gas for a proper combustion mixture and is obtained by establishing a communication between the variable pressure chamber 30 and a region of the air intake passage beyond the throttle in or adjacent an engine manifold connection 15. For this purpose, the carburetor section 12 is provided with a wall passage 60 which communicates with the main air passage through a control orifice 61. The passage 60 is connected through the fittings generally indicated at 62 with an adjusting screw chamber 63 on the top section 23 of the regulator. This adjusting screw or adjusting valve chamber 63 is equipped with a needle valve 64 which communicates with a horizontal chamber 55, such chamber opening into the top of pas-

sage 50' which has the ports 51 and 52 therein communicating with the variable pressure chamber. With this arrangement, it will be seen that on closing down the throttle to the correct idling speed, the regulated suction through 61, 60 and 62 to the valve 64 and through such valve to the variable pressure chamber 30 causes the pilot diaphragm to lower just the correct amount to supply the idle fuel. Such an arrangement is important in a regulator of this character, due to the fact that, with the full size venturi required for maximum power, the amount of gas drawn through the nozzle 19 when idling with the choke wide open is not easily regulated. Through the use of the passages and connections just described, a portion of the idle suction is transferred to the under side of the pilot diaphragm and is bled by the passages 50 and 50' which compensate for the violent suction above the orifice 61. The foregoing is also set out in said O. H. Ensign patent.

As has been previously pointed out it is one of the principal objects of this invention to provide a gas carburetor of the general character described above with means for supplying a combustible mixture of the proper proportions during cranking or starting speeds. For the satisfaction of this object, my invention contemplates the provision of a choke valve 68 which is shown as comprising a conventional disk valve 30 mounted across the intake end of the air passage 17 upon a shaft 69, the outer end of which is equipped with a lever member 70 for its manual actuation. The choke disk 68 is shown as being provided with an air orifice 72. When the valve 68 is closed, as is done during cranking operation, the suction created at this speed is sufficient to draw a relatively small volume of air through the orifice 72.

In order that the proper amount of gas may be supplied to the air intake passage while the choke is closed and the air is being drawn through the restricted orifice 72, it is important that the flow passage for the gas between the chamber 38 and the main air passage be likewise restricted. The restriction of the gas flow may be accomplished in various ways, but it is important for more satisfactory operation, that the restriction employed here be made adjustable to accommodate for different types of fuel. In the form of my invention, which is shown in Figs. 1 and 2, this is accomplished by completely cutting off the inlet opening to chamber 39 through the medium of a shutter valve generally indicated at 74, which in effect interposes a relatively severely restricted orifice 75 as the only passage between the chamber 38 and the interior of chamber 39. The orifice 75, which may be termed a "starting orifice", is equipped or associated with a needle valve 76 adjustable to control the flow therethrough. And while the passage 39 may have been referred to herein as a relatively unrestricted passage, it will be understood that an adjustable restriction is provided for the purpose of controlling the flow of gas therethrough. This last mentioned restriction is shown as comprising an adjustable valve member generally indicated by reference numeral 77 (see Fig. 2).

The shutter valve 74 is shown as comprising an elongated plate slotted as indicated at 80 and supported by a pivot 81, which extends through the slot. The plate 74 is biased upwardly toward the seating surface surrounding the bottom of passage 39, by means of a compression spring 82, supported by a washer 83 and a key 84 in 75

the bottom of the pivot pin 81. This valve 74 must be actuated simultaneously with the opening and closing movements of the choke valve 68 and for the purpose of effecting such movement, the choke shaft 69 is equipped with a collar 85, which carries a pin 86, such pin engaging in an opening 87 in valve plate 74.

For the purpose of holding the valve plate 74 in its two extreme positions of adjustment, illustrated in full lines and dotted lines in Fig. 2, a compression spring is interposed in the slot 80 between the pivot pin 81 and the rear end of the slot.

During starting operations the choke 68 is closed manually by means of the lever 70, such operation placing the shutter valve 74 over the lower end of the gas nozzle chamber 38, thereby closing the same. The throttle is then opened to about the position shown in Fig. 1 and upon cranking the engine there will be a positive suction of air through the orifice 72 and of gas through the orifice 75. The suction thus supplied in the gas chamber 38 will be positively communicated to passages 50-50' and through the port 51 to the under side of the pilot diaphragm 25. This suction, applied in the variable pressure chamber 30 below the pilot diaphragm, will depress the diaphragm and consequently actuate the pilot valve to ultimately open the main valve 25 in the manner previously described thereby supplying gas for the operation of the engine. As soon as the engine has turned over for a short period, the choke lever 70 is turned to immediately throw the choke valve 68 into its open position, it being preferred that no intermediate position be used. The opening of the choke valve 68 simultaneously opens the shutter valve 74 so that gas is then delivered to the air passage directly through the bottom opening of chamber 40 38 in which the valve 71 has been properly adjusted for normal operating conditions.

It has been previously pointed out as an additional object of this invention, to provide a carbureter capable of operating on either liquid or gaseous fuel, and in Fig. 5, I have illustrated one embodiment of my invention designed to accomplish this particular objective. In this form of my invention, I have shown a carbureter employing an air passage and a regulator similar to that described in connection with Fig. 1, such air passage being shown as embodying sections 13a and 12a similar to sections 13 and 12 of Fig. 1. The section 13a is equipped with a gas chamber indicated by reference numeral 38a, which receives the gas through a connection 37a from the regulator, generally indicated by reference numeral 10a. The regulator is supplied with gas through a valve indicated by reference numeral 33a, which may be selectively opened or closed to supply the carbureter with gas or liquid fuel as may be demanded by the particular operating conditions. The regulator is the same as that shown at 10 in Fig. 1, and for that reason is illustrated in outside elevation.

Gas is supplied to the throat of the venturi 16a through a gas tube 19a, mounted in a gas chamber 39a, such chamber incorporating a shutter valve 74a, which is operated in conjunction with the choke valve 68a in the same manner as was described in connection with Fig. 1. The regulator is also equipped with a gas pressure balance connection, generally indicated by reference numeral 51a and an idling connection generally indicated by reference numeral 62a.

Liquid fuel is supplied to the throat of the

venturi through a jet 89 from a constant level fuel chamber of any conventional type, indicated by reference numeral 90. The flow of fuel from intake 91 in the fuel chamber housing into the fuel chamber itself, is controlled by suitable valve means as indicated at 92, such valve means being of conventional construction, and being actuated by a float lever 93, which carries a float 93' on its free end, and is pivoted in the housing as indicated at 94.

The present form of liquid fuel supply unit for the combination gas and liquid carburetor shown in Fig. 5, is illustrated merely for the purpose of describing my invention, and is the same as that disclosed and described in the P. W. Ensign patent, No. 1,863,195, issued on June 14, 1932, and for a detailed description of this liquid fuel supply unit, reference is made to that patent. For the purpose of describing the present invention, it will be sufficient to point out that the section 12a, which contains the venturi of the air passage, also includes the idling by-pass, accelerating well, etc., indicated by reference numeral 95. The liquid fuel chamber 90 contains a block 96 which includes primarily the ports and passages 25 for controlling the initial metering of the liquid fuel from the supply reservoir to the main fuel passage 97, which communicates with the jet 89.

The space above the liquid level in fuel reservoir 90 is closed against direct communication 30 with the atmosphere, and suitable means is provided whereby the pressure in the air intake 17a is applied to the fuel in the reservoir. In this embodiment of my invention, the inlet pressure is communicated to the fuel reservoir by a passage comprising an annular chamber 100, which surrounds the upper end of the elbow section 13a. The annular chamber 100 communicates with the inlet 17a of the main air passage, through a substantially unrestricted passage indicated at 101, the passage 101 having an opening in the air passage 17a on the intake side of the choke valve 68a. The annular chamber 100 communicates with the fuel chamber above the liquid level therein through a passage shown in 40 dotted lines at 102 and a port 102'.

Fuel is taken from the reservoir into a vertical riser passage 103 in block 96, such passage comprising a portion of the main fuel passage, by way of a valve controlled orifice 104 in the end 50 of plug 105, which is screwed into a bore within the bottom of the block. The flow through the orifice 104 is controlled through the medium of a needle valve 105, which is urged upward into engagement with a screw cap 106 by means of a 55 spring 107 confined between the upper face of the block and a flange 108 on the upper end of the valve. The fuel admitted to the riser passage 103 through the valve controlled orifice flows upwardly and over the lower edge of an unrestricted opening 110 into passage 111, and from there it passes downwardly to the horizontal main fuel passage 97. A restricted flow of air is also taken into the passage 103 through a calibrated bushing 113 at its upper end, the fuel 65 and air being mixed in flowing through the opening 110, and the mixture is conducted downwardly to the passage 97. It will be understood that the size of the bore through the bushing 113 is accurately calibrated in order to adapt the 70 carburetor to different motors, and to supply a suitable amount of initial air for a mixture with the fuel within the limits permitted by the other coating parts of the carburetor.

For further details in the construction and op-

eration of the liquid unit of this combination carburetor, reference is again made to the P. W. Ensign patent hereinabove referred to, and at this time it is again emphasized that my invention does not contemplate or require the use of any specific liquid fuel supply unit. As a matter of fact, it is an important and novel feature of the invention that the gas supply unit described above may be employed as an attachment 10 for a conventional liquid carburetor to convert the same to a combination unit. In this regard, my invention contemplates the replacement of the air intake section of a conventional liquid fuel carburetor with a section corresponding 15 to the elbow 13 or 13a, which has a gas supply passage formed of a length such that its outlet opens substantially in the throat portion of the venturi.

In a combination carburetor of this character, 20 it is important that means be provided for avoiding undue wear in the parts of the liquid unit of the carburetor when the carburetor is being operated with gas fuel. It is also important that means be provided for shutting off the liquid 25 unit so that the combination carburetor can be selectively operated on gas or liquid, such carburetor being provided with a valve for shutting off the gas supply indicated at 33a referred to hereinabove. For the purpose of shutting off the 30 liquid supply unit and further to lock the float and the float control valve against vibration when the liquid fuel supply unit is shut off, I employ a float locking mechanism, generally indicated by reference numeral 120. This mechanism 35 embodies a bushing 121, threaded into a suitably formed boss 122 on the liquid fuel chamber housing 90, such bushing being internally threaded to receive a threaded adjusting stem 123 which is equipped with a thumb nut 125.

The upper end of this adjusting stem bears 40 against a plunger member 126, which carries a compression spring 127, engaging the under surface of the float lever 93 at its upper end. It will be seen that the adjusting screw 124 may 45 be advanced upwardly in its threads to raise the float lever into a position where it will lock the valve 92 in closed position, the spring 127 being compressed under this action to lock the float against vibration when the valve 92 is thus 50 closed. In the form described above, the gas control valve and the liquid control mechanism are illustrated as being independently operated. It may be preferable under some conditions of 55 operation to interconnect the gas and liquid controls so that the one is automatically shut off when the other is opened; one form of such connection is diagrammatically illustrated in Fig. 11 and will be referred to in detail later in the description.

In Figs. 6 to 10, inclusive, I have shown another 60 modified form of a combination gas and liquid carburetor of the special down-draft type. In this connection it should be understood that the forms as shown in Figs. 1 and 5 can be used either down-draft or up-draft by simply turning the whole carburetor element over. Referring to Fig. 6, the main air passage is shown as being comprised of sections 130, 131 and 132, the throttle valve indicated by numeral 20b, being located in section 132, and the choke valve 68b being situated in the section 130.

The gas passage 37b leading from a regulator similar to that shown in Fig. 5, communicates with a cylindrical valve chamber 134, which contains a cylindrical valve 135, attached to the

choke shaft 69b. This cylindrical valve 135 is cut away on one side, as indicated at 137, to provide an opening which normally leads to the gas inlet chamber 138-138'. The portion 138 of this chamber has an opening 139 communicating with the throat of the venturi 16b, and contains a screw valve 140 for restricting the gas flow, the required amount for normal operating condition.

The choke valve 68b is provided with an orifice 72b, and when the choke valve is closed, it will 10 be seen that the air is drawn into the suction passage through this orifice. Simultaneously with the closure of the choke valve 68b, it will also be seen that the skirt portion of the cylindrical valve 134 rotates around to close the passage 15 leading to the gas supply chamber 138. The closure of the main opening in passage 138' in this manner, in effect interposes between the connection 37b and the passage or chamber 138-138' a restricted passage indicated generally by reference numeral 75b.

The passage 75b, as shown in Figs. 7 and 7a, embodies a control chamber 143, communicating with chamber 138' through a port 143', the control chamber 143 being in communication with 25 the connection 37b through a passage 144-144'. The control chamber 143 carries a needle valve generally indicated by reference numeral 145, which is employed to control the restricted flow of gas through the restricted passage 75b during 30 starting operations, such needle valve adjustment corresponding to the adjustment shown in connection with the valve 76 in Fig. 2.

In this embodiment of my invention, a Pitot tube 58b enters the intake connection 17b on the 35 inlet side of the choke valve 68b and connects through pipe 59b to the upper side of the diaphragm in a suitable regulator, similar to that shown in Fig. 5, for the purpose of maintaining a pressure balance on the pilot diaphragm in the 40 manner described in connection with Fig. 1.

The idle opening 61b is connected through a connection 62b to idle adjustment valve means similar to that indicated at 63 in Fig. 1.

The liquid supply unit for the carburetor is 45 shown as comprising in a general way, a float chamber portion 150 cast on one side of the section 131. In this portion 150 is assembled the liquid or gasoline carburetor parts. A float 151 is attached to a float lever 152 pivoted at 153 50 and adapted to close the float valve, indicated generally by reference numeral 154. Fuel enters the connection 154 through the passage 155, and flows through the openings 156 to the valve seat.

The liquid fuel flows from the float chamber 55 159 through a fuel orifice 160, which is equipped with an adjustable needle valve 161 for controlling the flow therethrough. Needle 161 is adjusted by operating the milled head 162, such head being associated with a spring 163 interposed between the under side of the head and the top of the adjustment needle.

Fuel flowing through the orifice 160 enters the chamber 165, and from there passes through the riser passage 166 and the fuel nozzle 167 into the 65 air stream passing through the venturi 16b.

The liquid unit is equipped with a riser passage (best illustrated in Fig. 9) which embodies a tube 170, and passages 171 and 172, the tube 170 being restricted as indicated at 173. The tube 170 takes 70 out of the well chamber 165 at its lower end, thus drawing up the fuel to the chamber 171 which is provided with an air vent 175, equipped with an adjusting screw valve 176. The leg 172 of the idle passage terminates in a chamber 177 75

which, as illustrated in Fig. 10, communicates through two ports 178 and 178' with the throttle bore. These ports 178 and 178', it will be observed, are situated on opposite sides of the 5 throttle disk when in its closed position.

An economizer passage 180 connects from the air in the upper portion of the float chamber to a chamber 181, which has a bore 182 connecting with the throttle tube at a point above the edge 10 of the throttle disk when it is in its closed position. This economizer operates to cause a slight depression on the surface of the gasoline in the float chamber over that portion of the load which may be under throttle control, beginning slightly 15 above idle.

For the purpose of locking the float against vibration, and to also lock the float control valve in closed position when the carburetor is being operated on gas alone, I provide an adjusting 20 screw 190, which is shown as being mounted in a bushing mounting 191, such screw carrying a compression spring 192 and a plunger 193, which contacts a cross member 194 on the float lever mechanism below the lower end 154' of the float 25 valve. With this arrangement it will be seen that the float and float valve may be locked in a valve closing position, so that there is no wear in these parts due to vibration of the engine while the carburetor is being operated with gas alone.

30 A pressure balance is maintained on top of the liquid in the float chamber through a passage, such passage opening into the top of the float chamber and having a port 197 communicating with the air inlet portion of the suction passage.

35 As was previously stated in connection with Fig. 5, my invention contemplates the provision of means for interconnecting the gas inlet control valve 33a and the float and float valve locking mechanism 120 so that when one connection 40 is opened the other is automatically closed. In Fig. 11, I have shown one form of connection which may be employed for this purpose. In this construction the gas inlet connection 33c is shown as being equipped with a disk valve 200 45 mounted on a shaft 201, the extending end of which carries a lever 202.

The float lever 93c and the valve 92c are adapted to be urged upwardly into a locked position by a plunger member 203, which is slidably 50 mounted through suitable packing means in a bushing 121c. The bottom of the plunger 203 is attached to a bell crank 204, pivoted on a suitable bracket as indicated at 205. The other arm of the bell crank 204 is attached by means of a 55 link 206 to the lever 202.

A tension spring 207 is provided for the purpose of urging the linkage system to one of its extreme positions. In the form shown, the spring 207 holds the gas valve 200 closed and depresses 60 the plunger 203 so that the float and float valve are free to operate. An operating link or rod 209 is provided for controlling the position of these two valve means. Thus when it is desired to operate on gas, the rod 209 is drawn forward 65 in the direction of the arrow A to open the gas valve 200 and lock the float valve. Suitable latching means 210-211 may be provided for locking the rod 209 in this latter position. When the latch 210-211 is released the valve and float 70 locking mechanism are drawn back to the other extreme position (shown in full lines) by the action of the spring 207.

It is to be understood that while I have here described and illustrated certain preferred em- 75 bodiments of my invention, the invention is not

limited to the precise details of construction or the particular combination of parts described above, but includes within its scope whatever changes may fairly come within the spirit of the appended claims.

I claim:

1. The combination comprising: a gas carburetor including a suction passage connecting with an engine manifold and having an air inlet, an outlet and a throttle for controlling the flow of 10 fluids through said suction passage; means for delivering gas at substantially constant pressure to said suction passage, said gas delivery means including a relatively severely restricted starting orifice and a relatively less restricted normal 15 operating orifice; a choke valve in said suction passage at the inlet side of the point of fuel discharge from said fuel delivery orifices; means for closing said choke valve; a fuel control valve actuated with said choke valve for closing said 20 normal operating orifice; and means for admitting a restricted flow of air to said suction passage when said choke valve is closed.

2. The combination comprising: a gas carburetor including a suction passage connecting with an engine manifold and having an air inlet, an outlet and a throttle for controlling the flow of 25 fluids through said suction passage; means for delivering gas at substantially constant pressure to said suction passage, said gas delivery means including a relatively severely restricted starting orifice and a relatively less restricted normal 30 operating orifice; a choke valve in said suction passage at the inlet side of the point of fuel discharge from said fuel delivery orifices; means for closing said choke valve; and a fuel control valve actuated with said choke valve for closing 35 said normal operating orifice.

3. The combination comprising: a gas carburetor including a suction passage connecting with an engine manifold and having an air inlet, an outlet and a throttle for controlling the flow of 40 fluids through said suction passage; a pressure regulator having a gas intake and an outlet communicating with said suction passage, said regulator operating to deliver gas to the carburetor at substantially constant pressure, said regulator outlet being communicable with said suction passage by way of a fuel delivery passage; a choke valve in the suction passage at the inlet side of 45 the point of fuel discharge from said fuel delivery passage; a fuel control valve operated in accordance with movements of said choke valve to control the flow of fuel through said delivery passage, said fuel control valve closing said delivery passage when said choke valve is in closed position; and means for delivering to said suction passage at the outlet side of the choke valve, a restricted 50 flow of fuel when said fuel control valve is in closed position.

4. The combination comprising, a gas carburetor including a suction passage connecting with an engine manifold and having an air inlet, an outlet and a throttle for controlling the flow of fluids through said suction passage; a pressure regulator having a gas intake and an outlet communicating with said suction passage, said regulator operating to deliver gas to the carburetor at substantially constant pressure, said regulator outlet being communicable with said suction passage by way of a fuel delivery passage; a choke valve in the suction passage at the inlet side of 60 the point of fuel discharge from said fuel delivery passage; a fuel control valve operated in accordance with movements of said choke valve to 65 control the flow of fuel through said delivery passage, said fuel control valve closing said delivery passage when said choke valve is in closed position.

control the flow of fuel through said delivery passage, said fuel control valve closing said delivery passage when said choke valve is in closed position; and means for delivering to said suction passage at the outlet side of the choke valve, a restricted flow of fuel when said fuel control valve is in closed position, said choke valve having a relatively small air passing opening.

5. The combination comprising; a gas carbureter including a suction passage connecting with an engine manifold and having an air inlet, an outlet and a throttle for controlling the flow of fluids through said suction passage; a venturi at the inlet side of the throttle; a pressure regulator 10 having a gas intake and an outlet communicating with said suction passage, said regulator operating to deliver gas to the carbureter at substantially constant pressure; a fuel nozzle discharging into said venturi, said nozzle being communicable with said regulator outlet by way of a fuel delivery passage; a choke valve in the suction passage at the inlet side of said venturi; a valve operated in accordance with the movements of said choke valve to control the flow of fuel through said delivery passage; and means for delivery to said suction passage at the outlet side of the choke valve a restricted flow of fuel when said fuel control valve is in closed position.

6. The combination comprising; a gas carbureter including a suction passage connecting with an engine manifold and having an air inlet, an outlet and a throttle for controlling the flow of

fluids through said suction passage; a pressure regulator having a gas intake and an outlet communicating with said suction passage, said regulator outlet being communicable with said suction passage by way of a fuel delivery passage; a choke valve in the suction passage at the inlet side of the point of fuel discharge from said fuel delivery passage; a fuel control valve operated in accordance with movements of said choke valve to control the flow of fuel through said delivery 10 passage, and means for delivering to said suction passage a restricted flow of fuel when said fuel control valve is in closed position.

7. The combination comprising; a gas carbureter including a suction passage connecting with an engine manifold and having an air inlet, an outlet and a throttle for controlling the flow of fluids through said suction passage; a pressure regulator having a gas intake and an outlet communicating with said suction passage, said regulator operating to deliver gas to the carbureter at substantially constant pressure; a fuel nozzle in said passage; a manually operated choke at the inlet side of said nozzle; means including a fuel 15 passage for feeding gas to said nozzle; a valve movable with said choke valve to control the flow of gas through said fuel passage, and means for feeding to said suction passage a restricted flow of gas when the last mentioned valve is in closed position.
